UNITED STATES PATENT OFFICE.

ELLSWORTH E. CARLSON, JAMES P. COSTELLO, AND RALPH L. HEILBRONNER, OF MILWAUKEE, WISCONSIN, ASSIGNORS TO LUXITE SILK PRODUCTS CO., OF MILWAUKEE, WISCONSIN, A CORPORATION OF WISCONSIN.

BLOOMERS.

Application filed July 23, 1925. Serial No. 45,493.

This invention relates to improvements in bloomers and more particularly to bloomers of the type now worn rather generally by misses and ladies.

One object of the invention is to provide a crotch piece in a garment of the character described which shall be so constructed and arranged as to possess many advantages over the crotch piece of such garments as heretofore made, both with regard to wearing qualities and comfort to the wearer.

In the Decker & Scott Patent No. 1,277,700 of September 3, 1918, a crotch piece for bloomers is disclosed made up of two crescent-shaped sections secured together along their lower curved edges and arranged so that the seam thus formed provides a continuation of and a connection between the inner seams and the leg portions of the garment. The crotch sections of this patent are of warp knitted fabric with the warp threads extending vertically so that elasticity of the piece is in lateral directions. In the first place the crotch piece of this patent, due to its construction, bunches or gathers at the center as the legs of the garment are moved together, producing discomfort to the wearer and wear is concentrated on the adjacent portions of the seam due to the rubbing engagement between these portions as the legs are moved back and forth. Another objection to this crotch piece of the Decker & Scott patent is the absence of give or elasticity in vertical directions resulting in the belt portion of the bloomers being pulled down below the waist line of the wearer whenever a sitting or stooping posture is assumed and especially during participation in athletic exercises, for which bloomers of this character are much worn.

Another object of the present invention therefore resides in the provision of a crotch piece which will overcome these various disadvantages while at the same time affording greater wearing qualities and comfort.

Other objects of the invention will be apparent from the following description taken in connection with the accompanying drawings, wherein one form of the invention is illustrated.

In the drawings:

Figure 1 is a front view of a garment embodying the present invention;

Fig. 2 is a side view with one leg of the garment folded back;

Fig. 3 is a detail showing the front or back sections of the garment;

Fig. 4 is a detail view of the crotch piece sections; and

Fig. 5 is a sectional view taken on line 5—5 of Fig. 2.

Referring more in detail to the drawings, the garment of the present invention is shown as comprising a plurality of front sections 10 and 11 and a plurality of back sections 12 and 13. The outer adjacent edges of the sections 10 and 12 and 11 and 13 are stitched together as at 14 and 15 and the adjacent edges of sections 10 and 11 and 12 and 13 are stitched together as at 16 and 17 respectively in the body portion of the garment and also at 18 and 19 in the leg portions of the garment. The upper edge or waist line of the garment is provided with elastic tape or the like as are also the lower edges of the garment forming the leg openings.

The crotch piece, to which the present invention is primarily directed, is designated generally by reference character 20 and is made up of two identically formed shield-shaped sections 21^a and 21^b secured together along their upper curved edges 21^c as at 22. The crotch piece thus formed is combined with the garment as an insert as shown, said piece being stitched or otherwise secured to the sections 10, 11, 12 and 13 of the garment along the inner curved edges thereof, which extend from the lower ends of seams 16 and 17 previously described to the upper ends of seams 18 and 19 also previously described. The crotch piece is secured in position or combined with the garment in such wise that the seam 22 uniting the shield-shaped sections 21^a and 21^b extends centrally of the garment from front to rear thereof forming in effect a continuation of and a connection between the seams 16 and 17 in the body portion of the garment. The crotch piece sections 21^a and 21^b are of warp knitted fabric and these sections are united, and combined in the garment so that the warp threads of said sections extend in downwardly divergent lateral directions from the seam 22. In this manner the crotch piece is possessed of pronounced elasticity in vertical directions.

In this connection, the sections 21^a and 21^b are of warp knitted fabric and these sections are united, and combined in the garment so that the warp threads of said sections extend in downwardly divergent lateral directions from the seam 22. In this manner the crotch piece is possessed of pronounced elasticity in vertical directions. In this connection, the sections 21^a and 21^b are of warp knitted fabric and these sections are united, and combined in the garment so that the warp threads of said sections extend in downwardly divergent lateral directions from the seam 22. In this manner the crotch piece is possessed of pronounced elasticity in vertical directions.

nection it is to be noted that the crotch piece sections are angled, that is, diverging from the vertical seams 16 and 17. This disposition of the crotch piece sections coupled with the feature of having the warp threads of the sections extend in downwardly diverging lateral directions from the seam 22 so places the direction of the elastic phase of the crotch piece sections 10 that they yield to absorb vertical pull and preclude the possibility of the garment being pulled down at the waist when subjected to the various strains incidental to the use of the garment.

15 By forming the crotch piece, as described, of two shield-shaped sections united along their upper curved edges and combining the piece thus formed in the garment with the seam joining said sections extending centrally from front to rear, all tendency towards bunching or gathering of the material in the crotch when the legs of the garment are moved together is avoided. In other words, the legs of the garment may be 25 moved together without causing any distortion or abnormal condition at the center of the piece. This is due to the peculiar shape of the sections 21^a and 21^b, the manner in which they are united and their arrangement or combination in the garment. Another advantage resides in the entire elimination of seams on the inner leg portions of the garment as the crotch piece is devoid 35 of seams save the one 22 extending from front to rear of the garment. Accordingly undue wear such as inner leg seams invariably cause is avoided. Furthermore, by uniting the sections 21^a and 21^b so that the warp threads thereof extend downwardly in 40 divergent lateral directions from the seam 22 when the crotch piece is in position, maximum elasticity in vertical directions is obtained, adding greatly to the comfort of the wearer, for by reason of this feature 45 stooping, sitting or squatting postures may

be assumed without causing the garment to be pulled down at the waist.

As shown in the drawings, the crotch piece is formed of two-ply material, that is, each section, 21^a and 21^b, is made of double thickness, this being done for reenforcing purposes. It will of course be appreciated, however, that the crotch piece may be made of single ply and in some instances this may be preferred. It will be apparent that the improvements are also susceptible of various other changes and modifications without departing from the spirit of the invention and accordingly it is not desired to limit or restrict the same except where limitations appear in the appended claims.

The invention claimed is:

1. In a bloomer garment, a crotch piece comprised of two shield shaped sections of warp knitted fabric stitched together along their upper curved edges and combined in the garment with the said stitched edges extending from front to rear thereof and forming a continuation of the center body seam of the garment, the warp threads of 65 said sections extending in downwardly divergent directions from said seam and lying substantially parallel to the inner leg seams of the garment, the greatest elasticity of the fabric of the crotch piece being in a 70 direction transverse to the warp threads.

2. In a bloomer garment, a crotch insert comprised of two shield-shaped sections formed of warp knitted fabric, a seam uniting said sections along their upper curved edges, the warp threads of said sections normally extending in downwardly divergent directions from said seam, the greatest elasticity of the fabric of the crotch insert being 80 in a direction transverse to the warp threads.

In witness whereof we hereto affix our signatures.

RALPH L. HEILBRONNER.
